UNITED STATES PATENT OFFICE.

HENRY STARCK, OF LONDON, ENGLAND.

BAGPIPE-CHANTER.

1,069,200.

Specification of Letters Patent.

Patented Aug. 5, 1913.

Application filed October 30, 1909. Serial No. 525,426.

To all whom it may concern:

Be it known that I, HENRY STARCK, a subject of His Majesty the King of England, residing at 31 Drummond Crescent, Euston 5 Road, London, N. W., England, have invented certain new and useful Improvements in Bagpipe-Chanters, of which the following is a specification.

This invention relates to improvements in 10 wood and like wind musical instruments relating more particularly to bag-pipe chanters.

The principal object of this invention is to provide a chanter with an increased compass, throughout which the whole of the 15 notes are pitched in true relation with each other, and one which enables the performer to play, and without cross-fingering, in either major or minor keys; an attainment, 20 so far as I am aware, not heretofore accomplished in a bag-pipe chanter.

A further object is to provide a new wood and like wind instrument suitable for orchestra and other purposes.

25 The present ordinary Scotch chanter has in front seven holes along its length, one hole at the back and two vent-holes on either side at the bottom of the chanter, and enables the notes G, A, B, C, D, E, F, G, A, 30 to be produced, but imperfectly only, according as all or some only of the holes are stopped by the fingers.

The invention is illustrated in the accompanying drawing in which—

35 Figure 1 is an elevation of a three-keyed chanter arranged for natural fingering in the scale of A major and with a chart to the manipulation thereof. Fig. 2 is a similar view of the instrument shown in Fig. 1 with 40 additional keys for increasing and completing the compass to C $\sharp$ with a chart to the manipulation of the additional keys, and Fig. 3 is a similar view showing the instrument illustrated in Fig. 2 adapted for natural 45 fingering in the scale of C major, with a chart to the manipulation of the keys not included in that scale.

Referring to Fig. 1, I arrange the present 50 back note-hole of the ordinary Scotch chanter in the front and provide a normally closed key 1, adapted to be opened by the first finger of the left hand, the hole being of such a size and in such a position as to give the upper A in the treble clef. The present 55 first front note-hole of the ordinary Scotch chanter, I arrange at the back as shown in

dotted lines at 2. The position and size of the back hole 2 may be varied so as to give either a tone or a semitone below the A key, that is to say either the upper G or G $\sharp$. The 60 back hole 2 is covered in the usual way by the thumb of the left hand. The following front note-holes 3, 4, 5, 6, 7 and 8, down the scale, are covered respectively by the first, second and third fingers of the left hand and 65 the first, second and third fingers of the right hand. The position and size of the note-hole 8 are adapted to give the octave note A from the key 1 and the holes 3, 4, 5, 6 and 7 are adapted to give the desired tone and 70 semi-tones in the octave in the desired scale. Since the instrument as shown in this figure is arranged for natural fingering in the scale of A major, the back hole 2 is adapted to give G $\sharp$, the note-hole 3, F $\sharp$, the note-hole 4, 75 E $\sharp$, the note-hole 5, D $\sharp$, the note-hole 6, C $\sharp$, the note-hole 7, B $\sharp$, and the note-hole 8, A $\sharp$, while when all the note-holes and the key 1 are closed the instrument will produce the note G $\sharp$. I may, however, increase the 80 compass by two notes down the scale by the addition of two normally-open keys 9 and 10 adapted to be closed by the fourth finger of the right hand. In the instrument shown in the figure, the position and size of 85 the hole of the key 9 are arranged to produce the note G $\sharp$, and the hole of the key 10, F $\sharp$, the instrument with all note-holes and keys closed, being adapted to produce the lower E $\sharp$. I may also increase the compass of the 90 instrument above the key 1 up to the upper C $\sharp$, by the addition of further keys adapted to be operated by the thumb and first finger of the left hand. For instance as shown in Fig. 2, the upper B $\sharp$ may be produced by a 95 hole normally closed by a key 11 adapted to be opened by the thumb of the left hand, and C $\sharp$, by a hole normally closed by a key 12 adapted to be opened by the second joint of the first finger of the left hand, thus 100 providing the instrument with a compass in the scale of A major extending from the lower E $\sharp$ to the upper C $\sharp$.

It is obvious that, if desired, the position of the keys 11 and 12 relatively to the center 105 line of the instrument and operation thereof may be reversed, that is to say C $\sharp$ might be played by the thumb and B $\sharp$ by the first finger of the left hand.

Such an instrument may be adapted to 110 produce all the tones and semi-tones within the same compass by the further addition of

the following keys down the scale. The upper C $\sharp$ by a normally closed key 13 adapted to be opened to produce this note by the second joint of the first finger of the 5 left hand; A $\sharp$ by a normally closed key 14 adapted to be opened by the thumb of the left hand; G $\sharp$ by a normally closed key 15 adapted to be opened by the first finger or, it may be, by the second finger of the left 10 hand; F $\sharp$ by a normally closed key 16 adapted to be opened by the second joint of the first finger of the right hand, or, it may be, by the third finger of the left hand; D $\sharp$ by a normally closed key 17 adapted to be 15 opened by preferably the second joint of the first finger of the right hand; the lower C $\sharp$ by a normally closed key 18 adapted to be opened by the second finger of the right hand; the lower A $\sharp$ by a normally closed 20 key 19 adapted to be opened by the third finger of the right hand; the lower G $\sharp$ by a normally closed key 20 adapted to be opened by the fourth finger of the left hand, and the lower F $\sharp$ by a normally closed key 25 21 adapted to be opened also by the fourth finger of the left hand. Thus all the tones and semi-tones from the lower E to the upper C $\sharp$, may be produced by means of six front note-holes, one back note-hole and 30 fourteen keys, pitched in true relation to each other and without cross fingering.

Such an instrument may be adapted for natural fingering in any desired key, as C major for instance, as shown in Fig. 3. Referring to the keys and note-holes down the scale, the upper C $\sharp$ key 12, C $\sharp$ key 13, B $\sharp$ key 11, A $\sharp$ key 14, and A $\sharp$ key 1, remain 35 unaltered; a G $\sharp$ key 22 is substituted for the G $\sharp$ key 15, and the back note-hole 2 is altered so as to produce G $\sharp$ instead of G $\sharp$; the position of the F $\sharp$ key 16 is altered for 40 the production of F $\sharp$ to the position shown at 23; the position and size of the first front note-hole 3 are altered so as to produce F $\sharp$ instead of F $\sharp$ as shown at 24; the front note-holes 4 and 5 remain unaltered; the position of 45 the normally closed C $\sharp$ key 18 is altered to the position shown at 25 for the production C $\sharp$ and is adapted to be opened by the fourth finger of the left hand; the position and size of the note-hole 6 is altered for the production of C $\sharp$ instead of C $\sharp$ as shown at 26; the note-hole 7, the A $\sharp$ key 19 and the note-hole 8, remain unaltered; while the positions of the 50 G $\sharp$ and F $\sharp$ keys 9 and 10, and of the G $\sharp$ and F $\sharp$ keys 20 and 21, with respect to the center line of the instrument, are interchanged as 55 shown so that G $\sharp$ and F $\sharp$ keys 20, 21, can be opened by the fourth finger of the right hand, and the G $\sharp$ and F $\sharp$ keys 9 and 10 by the fourth finger of the left hand.

It will be understood that where reference has been made to the position of a note key, the size of the key-hole is also in a well-known manner a determining factor.

It is obvious that a mouth piece 27 as shown in Fig. 3 may be added if desired.

Having thus described my invention, what I claim as new and desired to secure by Letters Patent of the United States of 70 America is:—

1. A chanter having the hole for the upper A in the treble clef at the front, a pivotally mounted key, said key normally closing said hole, said chanter having a hole 75 below the hole aforesaid and situated at the back thereof and six following holes at the front.

2. A chanter having the hole for the upper A in the treble clef at the front, a 80 pivotally mounted key, said key normally closing said hole, said chanter having a hole below the hole aforesaid and situated at the back thereof, six following holes at the front and two supplementary holes 85 below the six holes aforesaid, keys over the supplementary holes, and means for normally retaining said keys in the open position.

3. A chanter having the hole for the upper 90 A in the treble clef at the front, a pivotally mounted key, said key normally closing said hole, said chanter having a hole below the hole aforesaid and situated at the back thereof, six following holes at the front and 95 two supplementary holes below the six holes aforesaid, keys over the supplementary holes, and means for normally retaining said keys in the open position, and means for increasing the compass of the chanter 100 above the upper A of the treble clef, comprising holes above the hole for the upper A aforesaid, and corresponding keys, said keys normally closing said holes and being opened by the thumb and first finger of the 105 left hand.

4. A chanter having the hole for the upper A in the treble clef at the front, a pivotally mounted key, said key normally closing said hole, said chanter having a hole below 110 the hole aforesaid and situated at the back thereof six following holes at the front and two supplementary holes below the six holes aforesaid, keys over the supplementary holes, and means for normally retaining 115 said keys in the open position, means for increasing the compass of the chanter above the upper A of the treble clef and means for increasing the compass of the chanter below the lower E in the treble clef comprising a hole below the hole for the lower E aforesaid, and a normally closed key, said key covering the hole below the lower E and being opened by the fourth finger of the left hand.

5. A chanter having the hole for the upper A in the treble clef at the front, a pivotally mounted key, said key normally closing said hole, said chanter having a hole 120 below the hole aforesaid and situated at 125

the back thereof six following holes at the front and two supplementary holes below the six holes aforesaid, keys over the supplementary holes, and means for normally retaining said keys in the open position, means for increasing the compass of the chanter above the upper A of the treble clef, means for increasing the compass of the chanter below the lower E of the treble 10 clef, and means for obtaining all the tones and semi-tones within said increased compass comprising additional holes, and nor-

mally closed keys, said keys covering said holes and being opened by the second, third and fourth fingers of the left hand and the 15 first, second and third fingers of the right hand.

In testimony whereof I affix my signature in presence of two witnesses.

HENRY STARCK.
